[57] CLAIM

The ornamental design of a combined multi-chute bird feeder with recapture bin, as shown and described in the drawings.

DESCRIPTION

FIG. 1 is a right side perspective view of a combined multi-chute bird feeder with recapture bin showing our new design;

FIG. 2 is a bottom plan view thereof;

FIG. 3 is a left side elevational view thereof;

FIG. 4 is a front elevational view thereof;

FIG. 5 is a top plan view thereof;

FIG. 6 is a rear elevational view thereof;

FIG. 7 is a right side perspective view of a second embodiment of FIG. 1; and,

FIG. 8 is a top plan view of FIG. 7, the bottom plan view being substantially identical to FIG. 2 except for the interior slotted trough and all other views are identical to the first embodiment.
